UNITED STATES PATENT OFFICE.

GEORGE R. COLEY, OF PORTLAND, OREGON.

COMPRESSION INNER TUBE FOR TIRES.

Application filed September 17, 1921. Serial No. 501,303.

To all whom it may concern:

Be it known that I, GEORGE R. COLEY, a subject of Great Britain, and resident of Portland, in the county of Multnomah, in the State of Oregon, U. S. A., have invented certain new and useful Compression Inner Tubes for Tires, of which the following is a specification, reference being had to the accompanying drawings.

10 My invention relates to means for inflating pneumatic tires, and has for its object the production of an inner, inflatable tube which, when filled with air at required pressure, will effectually resist deflation through 15 puncture.

My tube belongs to that class in which the walls of the tube are made of elastic material, such as india-rubber, that is thick or heavy in cross-section as contra-distinguished 20 from the thin, bladder-like tubes now in general use.

Heavy walls of that description possess two distinct advantages. One advantage they have over thin tubes is that when once 25 inflated they hold, by reason of their thickness, air without leakage, and require inflation only at long intervals of time, whereas, thin tubes, however apparently airtight, are porous, and are, therefore, subject to constant leakage, which, although imperceptible 30 at any instant of time, necessitate pumping up at short intervals in order to maintain effectual air pressure within the tube. This affords in itself one distinct gain in the use 35 of heavy tubes generally over thin ones, wherein my invention participates.

The second advantage referred to is that a heavy tube possesses, by reason of its elasticity, a transversely distributable potential 40 force, which it has been conceived to be possible to transmit through the body of the material composing the tube with the result of effectually closing said body against leakage of air by puncture. The necessity for 45 transmitting said force throughout the entire body of the tube does not appear to have been heretofore conceived.

The principle of excluding leakage in 50 pneumatic tires in the manner just referred to, that is, by compression laterally of the body of a thick, elastic inner tube, is already recognized in the art as theoretically practicable and desirable. The earliest proposal known to applicant for carrying that principle into effect is by providing in the tube 55 a circumferential channel formed by a fold

or depression in the body of the tube, which, upon inflation of the tube, is designed to fill the hollow of an encasing tire, with compressing effect upon the material composing 60 the body of the tube. It is found in practice, however, that such a channel or fold cannot be relied upon to effect, with certainty and completeness, the object intended. The reason is that it is impossible, by such means, 65

to attain in practice the end proposed in theory. If the channel is made too shallow, the tube, in rounding out to its full capacity, must either stretch or must simply, that is, without any or without sufficient compres- 70

sion, fill the space provided for its accommoda- 75

tion. In either case, effectual compression throughout the body of the tube will be lacking. On the other hand, if the channel is too deep, or, in other words, the fold constituting the channel is too voluminous, the effect of attempt at inflation of the tube to its capacity will be to produce a buckling in the body of the tube, thereby causing a 80

stretching of the material at certain points which defeats the purpose intended. Where- 85

fore, even if a tube having a single channel

be regarded as theoretically possible for the purpose under consideration, it is dependent for success upon such and so many minute factors, as to be commercially uneconomical 90

if not entirely impracticable.

The present invention has for its object the elimination of the above mentioned de- 95

fects in construction heretofore employed, and seeks to provide a tube which, when de- 100

flated, has a plurality of indentations adapt- 105

ed to be forced outwardly when the tube is inflated and thereby to compress the entire tube mass. Another object of the invention is to arrange the indentations in such a way that upon inflation of the tube and the setting up of the compressing stresses there is a complete balancing of the stresses, whereby the compression is uniformly distributed throughout the tube mass, and there is no tendency for the tube to move within the shoe. A further object of the invention has to do with the arrangement of the indentations in such a way that the tube is suitably 110

locked in position within the shoe when the tube is inflated and is properly centered automatically upon inflation.

The above and other objects of the invention of a more minute character, which are more intimately associated with the details of construction hereinafter described, are

accomplished by providing a tube having a plurality of series of indentations, preferably dish-shaped, the series being disposed circumferentially of the tube and in substantial parallelism. The series of indentations are divided by passive areas which are substantially continuous and extend circumferentially of the tube. These passive areas are arranged in parallelism and contact with the inner surface of a shoe while the tube is deflated. The individual indentations of the series are divided by transversely extending passive areas which contact with the inner surface of the shoe while the tube is deflated. These passive areas in each series are staggered with respect to the passive areas in the adjacent series, and the indentations of each series are staggered with respect to the indentations of the adjacent series.

20 What constitutes my invention will be hereinafter described in detail and succinctly set forth in the appended claims.

In the accompanying drawings,

25 Figure I is a side elevation, partly in longitudinal section, of a sector of a tire, showing my invention in present preferred form of embodiment.

Figure II is a transverse section on the line II—II of Figure I.

30 Figure III is a transverse section on the line III—III of Figure I.

Figure IV is a diagrammatical development of the inner tube, as shown in Figure I.

Referring to the numerals on the drawings, 1 indicates a pneumatic tire, which may be of any ordinary or suitable type designed and adapted to form a case for an inner, inflatable tube 2, from whose inflation in use it takes shape. The casing 1 is made of suitable wear-resisting material, and its construction may be varied according to preference. The inner tube 2 is made of elastic material like india-rubber, that is adapted, under inflation, to fit snugly against the 45 rounding wall of the encasing tire.

In commercial use, the tires and tubes are proportionate in size with a size of tube provided for each size of tire.

According to my invention, the outside diameter of each cross-section of tube is made substantially equal to the inside diameter of its tire, which allows for the slight inequalities that occur in manufacture. Consequently, if the inner tube were circular in shape, its outside wall would touch the inside wall of the tire, substantially at all points, as indicated partially by dotted lines 3 in Figures II, and III. The said contact is in fact always preserved in respect to portions of the tube 2, 55 but in respect to the remaining portions of the tube, there is contact only during inflation. When the tube is deflated, and when it is introduced into the interior of the tire 1, the dish-shaped patches constituting compression elements 5 are not in contact with

the inside wall of the tire, but are, by their own resiliency, set inwardly into the hollow of the tube 2. When the tube is inflated, under required internal air pressure, the elastic material composing the elements 5 is compressed by being crowded into restricted openings provided for their respective accommodation in the walls of the tube. Whereupon, each of said elements exerts a laterally expansive force that communicates itself, with compressing effect, upon the whole mass of elastic material constituting the tube.

70 In order to render the entire mass effectively permeable to the influence of said force, areas of demarkation are provided in the walls of the tube between the compression elements 5, along lines circumferential to the tube, of which there are preferably four, designated, respectively, by the numerals 6, 7, 8, and 9. Also, along lines 10 there are cross areas extending between such of the lines 6 to 9 as are next adjacent to each other. Along the lines 6, 7, 8, 9 and 10, respectively, there is constant contact 90 with the tire 1 while the latter encases the tube 2. The term line in the above connection is intended to designate general disposition of contacting areas, and is not to be construed to be limited to lines of mathematical exactitude. Understood accordingly, the lines 6 to 10 indicate the location, also, of what may be aptly termed passive areas, because they are areas that receive force from the elements 5, which are the active agents of compression. In a sense, the said areas, after they are charged with force by the functioning of the elements 5, become active agents for healing punctures; but that is due only to retroaction, and during 105 inflation of the tube 2.

Because of the passive nature of the areas aforesaid, it is necessary that their respective transverse dimensions should be reduced to such a minimum as the compression derived from the active elements 5 may effectively penetrate, it being taken into consideration that each of said areas is acted upon directly by not less than two active elements. Consequently, as storage reservoirs 115 of force, each of said areas receives contribution of force from not less than two active or compression elements. In fact, all of the compression elements coact indirectly, and, in some measure, to store up force throughout the entire elastic mass composing the tire; and it is only with a view to clearness, through simplicity of statement, that the direct action of the compression elements is emphasized.

120 125 130 It should be noted in this connection, that the disposition of the lines of passive areas is determinate with respect to the tube encasing tire, and that the operative action of the elements 5 takes place between them with-

- out materially disturbing their relationship to the tire. This constitutes one feature of my invention that is important and distinctive, inasmuch as it affords effective means 5 for storage of energy throughout the mass of the tube. By it, in considerable measure, is effected a balancing of force against force, without which, or without some such provision, a force of compression generated in 10 one part of a tube might be absorbed, and, in effect, lost in passive areas of excessive extent.
- It is also noted that, upon inflation of my tube 2, no stretching thereof anywhere occurs. Inflation serves only to compress the elements 5 to the point of contact with the inner face of the tire 1, which resists any stretching tendency. It is compression only that does the work.
- 20 What I claim is:
1. An inner tube for pneumatic tires having, in deflated condition, a contour to fit the inside of a shoe and provided throughout its entire area with a plurality of circumferentially extending series of indentations, which indentations upon inflation of the tube within a tire, are forced outwardly by the filling air to compress the remainder of the tube mass, said series being separated 25 by passive areas adapted normally to contact with the inside of the tire shoe, the passive areas being substantially continuous in straight lines circumferentially of the tube.
  2. An inner tube as specified in claim 1, 30 the individual members of each series being divided by passive areas extending transversely of the tube, there being a plurality of such passive areas in each series and said passive areas in the adjacent series being 35 staggered with respect to each other.
  3. An inner tube for pneumatic tires having, in deflated condition, a contour to fit the inside of a shoe, and provided throughout its entire area with an assemblage of indentations, which indentations, upon inflation 40 of the tube within a tire, are forced out- wardly by the filling fluid to exert a compressing effect upon the entire mass of material composing the tube, said indentations being arranged in a plurality of substantially parallel series extending circumferentially of the tube and divided by substantially parallel continuous passive areas extending in straight lines circumferentially of the tube, said passive areas normally contacting with the inner surface of a shoe before the tube is filled with air and the individual indentations of each series being staggered with respect to the indentations in the adjacent series. 50
  4. An inner tube for pneumatic tires having, in deflated condition, a contour to fit the inside of a shoe, and provided throughout its entire area with an assemblage of indentations, which indentations, upon inflation of the tube within a shoe, are forced outwardly by the filling fluid to exert a compressing effect upon the entire mass of material composing the tube, said indentations being arranged in a plurality of substantially parallel series extending circumferentially of the tube and divided by substantially parallel continuous passive areas extending in straight lines circumferentially of the tube, said passive areas normally contacting with the inner surface of a shoe before the tube is filled with air and the individual indentations of each series being staggered with respect to the indentations in the adjacent series, and transversely extending 60 passive areas between the individual indentations of each series and normally contacting with the inside of the shoe before the tube is filled. 65

In testimony whereof, I have hereunto set 85 my hand in the presence of two subscribing witnesses.
